UNITED STATES PATENT OFFICE.

ANDREW EPPLER, OF LYNN, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

SOLE-LAYING MACHINE.

1,283,709.

Specification of Letters Patent.

Patented Nov. 5, 1918.

Application filed September 21, 1917. Serial No. 192,616.

To all whom it may concern:

Be it known that I, ANDREW EPPLER, a citizen of the United States, residing at Lynn, in the county of Essex and State of Massachusetts, have invented certain new and useful Improvements in Sole-Laying Machines; and I do hereby declare the following to be a full, clear, and exact description of the invention, such as will enable others skilled in the art to which it appertains to make and use the same.

The present invention relates to machines for laying soles upon boots and shoes and is shown more particularly in connection with a machine of the type disclosed in the patent to Davenport No. 1,066,473, July 8, 1913.

This type of machine is provided with a yielding pressing pad which is designed to force all portions of a shoe sole into contact with a shoe bottom upon which the sole is to be laid. For this purpose the pressing face of the pad is curved to correspond to the general contour of the shoe bottom and is provided with oppositely disposed shoulders or projections adapted to engage with the shank portions of the sole and force the latter into contact with the shoe bottom. As these raised portions or shoulders engage the sole with the greatest pressure it follows that there is a tendency during the continued operation of the machine to cause a depression of the shoulders and a consequent flattening out of the pad so that the latter does not perform its function of shaping the sole to the shoe bottom, especially at the shank.

The object of the present invention is to improve sole laying machines of the type described embodying a yielding pressing pad in such a manner that the range of usefulness and efficiency of the pad is greatly increased. Accordingly with this object in view a feature of the invention consists in the combination in a sole laying machine provided with a yielding pad having a curved pressing face corresponding to the contour of a shoe bottom, of means co-operating with the pad beneath a projecting shoulder and arranged to raise the shoulder from the surface of the pad. This construction not only permits the restoration of the pad to its initial shape after it has become flattened out through long continued use,

but provides for the requisite adjustment of the pad when operating upon different styles of shoe bottoms in which the shape to be imparted to the sole may vary widely.

In the simplest and most efficient form of the invention which has yet been devised an adjusting wedge is located in the side of the pad opposite a shoulder and may be moved to raise the shoulder from the surface of the pad.

In the accompanying drawings illustrating the preferred form of the invention, Figure 1 represents a view of the improved pad with the adjusting means incorporated therein; Fig. 2 is a bottom plan view of the pad shown in Fig. 1; and Fig. 3 is a cross section in elevation of the pad taken upon the line 3—3 of Fig. 2.

The sole laying machine is provided with a shoe supporting jack, a co-operating pressing pad and actuating mechanism designed to relatively move the jack and pad to apply a direct pressure to the shoe sole and shape the sole approximately into conformity with the shoe bottom. The pressing pad is made of rubber and is sufficiently yielding to permit the pad to accommodate itself to irregularities in the shape of the shoe bottom or slight discrepancies between the shape of the shoe bottom and the shape of the pad. As shown clearly in the drawing, the pad comprises a body portion 10 having a curved pressing face 12 and oppositely disposed shoulders 14 adapted to engage with and press down opposite margins of the sole at the shank, the heel seat of the sole resting substantially on the portion 15 of the pad.

It is desirable that the shoulders 14 of the pad shall have a sufficiently pronounced curvature to round the shank of the sole and cause the marginal portions of the shank to hug closely to the last. As these raised portions of the pad bear upon the sole with a greater pressure than certain other portions of the pad, the tendency of the pad is to flatten out so that the sole, especially at the shank, is not properly shaped to the shoe bottom. This disadvantage is overcome in the present invention through the use of an adjusting wedge supported behind the shoulder or other raised portion of the pad and having provision for adjustment to force the shoulder outwardly with respect to the surrounding surface of the pad. In the illus-

2
trated embodiment of the invention a pair of wedges are received in opposite sides of the pad behind the shoulders 14 and are supported upon a single rod passing through the pad. These wedges have provision for adjustment relative to the rod to cause them to enter the pad, forcing the shoulders outwardly from the surface.

A pair of adjusting wedges 17 enter correspondingly shaped recesses formed in opposite sides of the pad behind the shoulders 14. These wedges are supported upon a rod 18 extending transversely of the pad between the upper and lower surfaces and having adjusting nuts 20 threaded thereon which engage with the wedges and serve to force them into the pad to spread the surfaces on opposite sides of the wedges. From an inspection of the drawings it will be observed that each wedge is elongated and is provided with opposite curved surfaces 21 converging to a knife edge 22 and shaped approximately to the curvature of the shoulders 14. In order to facilitate an independent adjustment of the wedges and permit one of the shoulders to be forced out from the surface of the pad more than the other, means are provided for retaining the rod against movement relative to the pad. To this end a retaining plate 24 is received in a longitudinal slot 25 formed in the pad and is connected to the rod 18 by oppositely disposed collars 26. With this construction either wedge may be forced to enter the pad by a simple manipulation of the adjusting nut. It will be noted from an inspection of the drawings that the retaining plate 24 is provided with a vertical slot 27 which embraces the adjusting rod 18 to permit the convenient insertion of the plate after the rod has been assembled within the pad.

It will be observed that this construction not only permits the restoration of the shoulders to their original form if they should become flattened out through long continued use, but enables the curvature of the pad to be varied if so desired for operation upon different styles of shoe bottoms. For example, if the pad is designed particularly for the laying of soles upon shoe bottoms having a substantially flat shank they may likewise be adapted for laying soles upon shoe bottoms having a well rounded shank through the proper adjustment of the wedges to secure a greater projection of the shoulders from the surface of the pad.

While it is preferred to employ the specific construction and arrangement of parts shown and described, it will be understood

that this construction and arrangement is not essential except so far as specified in the claims, and may be changed or modified without departing from the broader features of the invention.

65

The invention having been described, what is claimed is:

1. A pressing pad having a yielding body portion provided with a curved pressing face, and means embodied in the body portion of the pad for varying the curvature of the pressing face.

2. A pressing pad of yielding material having a curved pressing face provided with a projecting shoulder adapted to engage with the shank portion of a sole, and means embodied in the pad for varying the projection of the shoulder from the surface of the pad.

3. A pressing pad for sole laying machines comprising a yielding body portion having projecting shoulders adapted to engage with opposite sides of the shank portion of a shoe sole, a pair of wedges received in opposite sides of the body portion of the pad behind the shoulders, and means for adjusting the wedges to vary the projection of the shoulders from the surface of the pad.

4. A pressing pad for sole laying machines comprising a yielding body portion having a curved pressing face, an adjusting rod passing through the pad, a pair of wedges supported upon opposite ends of the rod and received in opposite sides of the pad, and means for adjusting the wedges relative to the pad.

5. A pressing pad for sole laying machines comprising a yielding body portion having a curved pressing face, a rod extending across the body portion of the pad, a retaining member connecting the rod with the body portion of the pad to prevent endwise movement of the rod relative to the pad, a wedge supported upon the end of the rod and received in one side of the pad, and means for adjusting the wedge lengthwise of the rod.

6. A pressing pad for sole laying machines comprising a yielding body portion having a curved pressing face provided with oppositely disposed shoulders to engage the shank portion of a shoe sole, a rod extending across the pad, a wedge received in the side of the pad behind each shoulder, and connections between the wedges and rod for independently adjusting the wedges relative to the pad.

ANDREW EPPLER.
